UNITED STATES PATENT OFFICE.

WILLIAM E. S. STRONG, OF FALMOUTH TOWNSHIP, BARNSTABLE COUNTY, MASSACHUSETTS, AND NELSON MACY, OF GREENWICH, CONNECTICUT.

BOOK-LOCK.

1,156,641.

Specification of Letters Patent.

Patented Oct. 12, 1915.

Application filed August 10, 1914, Serial No. 856,043. Renewed June 30, 1915. Serial No. 37,394.

To all whom it may concern:

Be it known that we, WILLIAM E. S. STRONG and NELSON MACY, citizens of the United States, and residents of Falmouth 5 township, in the county of Barnstable and State of Massachusetts, and Greenwich, in the county of Fairfield and State of Connecticut, respectively, have invented certain new and useful Improvements in Book-10 Locks, of which the following is a specification.

This invention relates to means for locking the covers of books in closed position, such as books of record of business estab-15 lishments, and the main object thereof is to provide such locking devices which, when not in use, are entirely contained within the covers of the book, and which, whether in or out of operative position, do not present any 20 portion thereof upon the surfaces of the book and, for this reason, cannot deface the surfaces of desks, tables, or the like upon which the book may be placed.

Our invention is fully described in the 25 following specification, of which the accompanying drawings form a part, in which the separate parts are designated by the same reference characters in each of the views, and in which:—

30 Figure 1 is a perspective, fragmentary, view of a book provided with our invention, in locking position, and partly broken away to show the construction; Fig. 2 is a section therethrough, taken on the line 2—2 of Fig. 35 4; Fig. 3 is a view similar to Fig. 2, but showing the lock in inoperative position; and Fig. 4 is a section taken on the line 4—4 of Fig. 2.

In the drawings forming a part of this 40 application we have shown a present preferred form of embodiment of our invention, comprising a book, the body or leaf portion of which is shown at 5, and the upper and lower covers at 6 and 7, respectively, which covers our lock 8 is adapted to secure against unwarranted opening.

The upper cover 6 is recessed at 9 to receive a frame comprising, in the form shown, longitudinal tubular members 10 50 joined by transverse tubular members 11 and 12, the former of which is at the inner end of the frame, and the latter at a point intermediate the ends of the members 10 to form a pocket 13, said members 10 being 55 interiorly slotted, as shown at 14 for the dis-

tance between the members 11 and 12, and the last named members being secured in position in the recess 9 by means of pins 15, or equivalent, and the frame members are soldered or otherwise secured together in 60 the form shown in Fig. 4.

Slidable in each of the tubular members 10 is a bar 16 pivoted, by means of a pin 17, to a supplemental bar 18 at the edge of the book cover, the bars 18 jointly supporting a lock casing 19 provided with a key-hole 20 and any suitable lock mechanism, not shown, may be contained within the casing 19 for locking engagement with a lock member 21 on the lower book cover 7, and it 70 will be noted that the supplemental slide bars 18 are made of a length approximating the thickness of the book, as clearly shown in Figs. 1 and 2, and the length of the frame formed by the tubular members 10, 11 and 12 is made accordingly.

By reference to Fig. 2 it will be seen that the inner and outer surfaces of the cover 6 are not marred by slots, recesses, or the like, but preserve their normal continuity, the 80 only indications of a lock, when the book is unlocked, being the front opening of the recess 9 and the lock member 21, but we do provide, preferably, a thumb-nail notch 22 in the edge of the inner surface of the cover 85 6, whereby the lock casing 19 may be withdrawn from said recess, and it will also be seen that two guide pins 23 project into the corresponding frame slots 14 whereby they serve not only as guides but also as limiting 90 stops for the outward movement of the lock casing.

We prefer, as illustrated, to make the frame of square tubing, to reduce the diameter thereof for a given degree of strength, 95 but this is not essential as other configurations in cross section may be as readily employed, the main feature of the invention being to preserve an unbroken surface upon each of the covers to prevent marring of a 100 desk or the like, for a book lock, and also to entirely bury the lock casing and connected parts when the book is unlocked, and we may also, though not so shown, slide the lock member 21 into the cover 7.

Having fully described the invention, what we claim as new, and desire to secure by Letters Patent, is:—

1. The combination with the covers of a book, of a lock casing slidable in one cover, 110

and a lock member on the other cover, said first named cover being recessed to receive said lock casing.

2. The combination with the covers of a book, of a lock casing slidable in one cover, a frame in said cover for guiding said lock casing, and a lock member on the other cover, the surfaces of said covers being unbroken.

10 3. The combination with the covers of a book, of two jointed bars guided in one cover, a lock casing carried at the outer ends thereof, a lock member on the other cover,

and means for limiting the outward movement of said bars, the surfaces of said covers 15 being unbroken.

In testimony that we claim the foregoing as our invention we have signed our names to this specification in the presence of two subscribing witnesses.

WILLIAM E. S. STRONG.
NELSON MACY.
